8 Claims. (Cl. 175—366)

1

This invention relates to the manufacture of selenium rectifiers and more particularly to the electrical treatment thereof.

In the manufacture of selenium rectifiers it is well known that, after selenium has been applied to a base plate and subjected to a suitable heat treatment, and a counter electrode has been applied, it is necessary to apply a voltage in the reverse direction of the rectifier for some time in order to build up a relatively high resistance in the reverse direction.

In order that this resistance in the reverse direction should be built up it has hitherto been necessary to increase the applied voltage in steps as the resistance increased, the fall of current being taken as an indication of the increase of the resistance.

By using rectified alternating current or pulsating direct current the voltage finally applied is about 20 volts.

In carrying this out on a commercial scale, a blast of air is blown past the rectifiers to keep them cool. It has also been proposed to avoid undue heating and consequent damage to the rectifiers to apply a relatively high voltage to a rectifier for relatively short periods between which the rectifier is allowed to cool or positively cooled by an air blast. The relatively high voltage thus referred to was first 15 volts and then 20 volts.

Difficulties arise in applying electrical treatment on a manufacturing scale in that although good results are sometimes obtained it frequently happens that the current remains at a given value for an inordinately long period or even refuses to fall at all. Moreover, even with air blast cooling some rectifiers are damaged by burning. Furthermore the necessity for constant attention to increase the voltage in steps is a disadvantage.

According to one feature of the present invention the electrical treatment consists in applying a direct current source to a plurality of circuits in parallel, each circuit consisting of a single rectifier and an individual resistance.

These resistances serve several functions which will be clear from the following.

A very important function of the resistance used in series with each rectifier is that it enables the final voltage to be impressed in the first place without the necessity of raising it by steps. If E

be the impressed voltage, r the reverse resistance of the rectifier, which varies and gradually rises, R the resistance in series with the rectifier, V_P the voltage across the rectifier at any instant, i the current through the rectifier at any instant, then

$$V_P = i \cdot r, \text{ but}$$

$$i = \frac{E}{R+r} \therefore V_P = E \frac{r}{r+R}$$

If

$$\frac{r}{R} = n$$

15 then

$$V_P = \frac{n}{n+1} E$$

As r increases during the treatment, n increases and

20

$$\frac{n}{n+1}$$

increases and tends towards a final value of 1 when $V_P = E$.

25 Thus the presence of a resistance of appropriate value has the effect of automatically causing an increase of voltage across the rectifier as its resistance rises. In consequence the attention required to increase the applied voltage at intervals

30 is dispensed with, thus rendering the process cheaper. It has been shown by experience that the total time required is not increased by the presence of these resistances whilst the total energy in watt-hours required is somewhat less.

35 Rectifiers as initially manufactured differ in their rectifying properties and in treating a large number of rectifiers in parallel, initially poor rectifiers shunt the initially good rectifiers and so prevent the current necessary to build up a reverse resistance from passing through the latter.

40 An individual resistance in series with each rectifier tends to limit this shunting effect. It should be noted that a common resistance in series with all the rectifiers would increase the ill effects of initially poor rectifiers in shunting the initially good rectifiers.

45 We have also found that a given quantity of electricity through each unit area of rectifier is required to build up a satisfactory reverse resistance. This quantity is from 250 to 400 cou-

50

lombs per square centimetre. It follows that the time required for the electrical treatment can be reduced if the current density through each rectifier can be increased, the limiting factor being solely the rise in temperature of the rectifiers and consequent burning out.

We have found, however, that the time of electrical treatment can be reduced to about one hour and a very high current density (of 110 ma. per square centimetre initially) be safely used if the rectifiers are efficiently cooled. In order to achieve this, according to a further feature of the present invention the rectifiers are supported during the treatment upon a flat shelf through which cooling water is circulated, means for ensuring good contact with the flat surface of the shelf being provided.

We have found that a selenium rectifier behaves as if it consisted of a rectifying resistance and an ohmic resistance in parallel, the value of the latter varying from 20,000 ohms per square cm., for a good rectifier to 3,000 ohms per square cm. for a poor rectifier. It is only the current through the rectifying resistance that is effective in building up the rectifying properties. As this reverse rectifying resistance is built up the portion of the current flowing therethrough decreases as the applied voltage increases and the portion of current flowing through the ohmic resistance increases. For low current densities therefore, the portion of current flowing through the rectifying resistance may become too small to be effective and the phenomenon previously referred to may occur, viz: that the current through the rectifier disc may remain at a given value for an inordinately long time, or even refuse to fall at all. For high current densities, however, sufficient current passes through the rectifying resistance portion despite the shunting effect of the ohmic resistance to build up the resistance thereof during the whole time of electrical treatment. The resistance which, according to the invention, is connected in series with each individual rectifier, then serves to limit the current through the shunt ohmic resistance, when the reverse resistance approaches its maximum, to control the heat losses in such ohmic resistance. Thus the use of high current densities enables the time of treatment to be shortened in greater proportion than the increase in applied voltage, provided excessive heat losses are avoided and efficient cooling to prevent burning of the discs is used.

We have found that it is necessary to secure good heat conducting contact between the rectifiers and the surface of a flat metal channel through which cooling water is circulated. Circular rectifier discs are normally made with a base plate which is slightly concave at the back and we have found it necessary in the case of discs of 84 and 112 mm. in diameter to use a pressure of between 20 and 40 pounds to ensure that the base plate is in contact with the cooling surface throughout the whole area of the former and thus to ensure adequate cooling of the rectifier. For smaller size discs a smaller pressure is sufficient. With this form of apparatus we use a resistance of 170 ohms per square cm. area in series with each rectifier.

In order to keep the temperature drop in the cooling water for the rack small, the water is preferably circulated rapidly and a refrigerating plant used to cool the circulated water.

The best forms of electrical treatment and cooling apparatus known to us are described in the

following with reference to the accompanying drawings in which:

Fig. 1 is a perspective view of a portion of an apparatus for electrical treatment of circular selenium rectifiers of 84 mm. or 112 mm. diameter discs.

Fig. 2 is a front view, with a part in section of an apparatus for electrical treatment of lesser diameter selenium rectifiers.

Fig. 3 is a view partly in side elevation and partly in cross-section of another form of apparatus.

Fig. 4 is a view in cross section of still another form of apparatus.

Referring now to Fig. 1, a flat hollow shelf 10 is provided, through which cooling water is circulated from an inlet pipe 11 to an outlet pipe (not shown). Along the rear of the upper surface of shelf 10 is a strip 12 having a curved front portion to allow rectifier discs 14 to be inserted partly thereunder, screws 13 protruding on the under side to locate the discs 14 in position. The hollow shelf 10 is supported from a framework (not shown) which supports a member 15 of channel section at a little distance above the shelf 10. Flexible metal bellows 17, one for each rectifier disc are supported on individual supporting and insulating plates 16 secured to the member 15, the latter being cut away to allow of flexible tubing 18, connected to the bellows, passing through the member 15 to the rear thereof. Each flexible tube 18 is connected in rear of the member 15 to a pipe 19 connected to a suitable compressed air supply (not shown) a suitable cock or tap being provided to shut off the supply. The shelf 10 forms one common terminal of the electric supply and makes contact with the base plate of each rectifier whilst an apron member 20 attached to each bellows makes contact with the counter electrode of its individual rectifier when compressed air is admitted to the bellows. Each apron member 20 is provided with a terminal tag 21 which is connected by a conductor 22 to one terminal of a switch 23 mounted in rear of the member 15. The operating member 30 of switch 23 is adapted when moved to one side to connect conductor 22 to a conductor 28 and when moved to the other side to connect conductor 22 to conductor 29, the middle portion being an off-position. Conductors 28, 29 are connected to clips 26 and 27 which are supported in an insulated manner on the framework and carry resistances 24 and 25 of different values, provided with a common terminal 31. The other side of the direct current supply used for the electrical treatment is connected to all the terminals 31. The resistances 24 and 25 are of values adapted for rectifier discs of 84 and 112 mm. diameter and accordingly the front of member 15 is suitably marked with 84 on one side of each switch member 30 and with 112 on the other side so that the operator can initially by manipulation of the switch members 30 connect in the correct value of resistance for each rectifier. The member 12 is mounted on side members 32, one only of which is shown, which members 32 are in turn held on shelf 10 by screws and butterfly nuts 33. Each screw passes through an elongated aperture 34 in member 32 so that member 12 may be drawn forward such a distance that the screws 13 therein will properly locate the smaller of the two sizes of disc for which the apparatus is adapted.

The bellows 17 serve not only to press the centre of each disc against the surface of the

flat shelf 10 but help to cool the upper surfaces of the discs.

It is to be noted that the rectifier discs to be electrically treated in this apparatus are constructed in accordance with U. S. Patent No. 2,314,104 granted March 16, 1943 to E. A. Richards and L. J. Ellison, entitled "Metal rectifiers" an area around the central aperture of each being covered with insulating varnish before the counter electrode is sprayed thereon. The pressure is exerted upon this part at which the counter electrode is not in contact with the selenium. These remarks also apply to the apparatus shown in Figs. 2 and 3. In all forms of the apparatus the resistances mounted in series with the rectifier discs are separated physically from these discs, so that heat developed in the resistances does not add to the difficulties of cooling.

Referring now to Figs. 2 and 3, which show apparatus used for the electrical treatment of rectifier discs of 67 mm. and 45 mm. in diameter, cooling water is circulated through a hollow flat shelf 10 by means not shown. The shelf is provided on its upper surface with means for locating rectifier discs of either of two different sizes similar to the means shown in Fig. 1.

A conical helical spring 35 is provided for each rectifier, the base of each spring being anchored to a common frame member 38 bolted to upright members 39 of the framework. The lower end of each spring is fixed to a rod 36 which carries a contact member 37. All the members 37 are held in the positions shown by a common member 40 which rests upon two cams 41 fixed on respective shafts 42 journaled in front and rear members of the framework. Fixed also to shafts 42 are cranks 43 finished with handles 44 by means of which shafts 42 may be rotated to raise and lower member 40. When the rectifier discs to be treated are in position upon plate 10, the member 40 is lowered and springs 35 thus allowed to press contact members 37 upon the centre portion of the rectifier discs. Each contact member 37 is connected by a strip 45 to a conducting post 46 which in turn is connected by a flexible conductor to one terminal of a switch member (not shown). This switch member is similar to the member shown in Fig. 1 and is for the purpose of connecting a resistance of one or other value in series with each rectifier.

Fig. 4 shows in cross-section an apparatus for electrical treatment of rectifier discs of 25 mm. or 18 mm. diameter. For discs of this size a lighter pressure is sufficient and accordingly each disc 47 is pressed against the surface of the flat hollow plate 10 by means of a flat spring 48 bent into the approximately elliptical shape shown. Each spring 48 is attached to an individual thin flexible strip 49 connected to a terminal post 50 mounted on a horizontal frame member 51 extending across the rear of the apparatus. All the springs 48 are secured by means of screws 52 to a flat bar 53 extending along them all and mounted on the ends of leaf springs 54 (one only of which is shown) one at each end three of. The other ends of leaf springs 54 are secured to respective plates 55 fixed to the framework. Extending forwardly of bar 53 at each end and secured to the bar is an arm 56 a depression of which is engaged by a lug 57 on a lever 58 pivoted at 59 to the framework. A rod 60 furnished with a handle 61 is attached to each lever 58. In the position shown in the drawing the flat bar 53 is held down with each

spring 48 passing on a rectifier disc 47 by the weight of levers 58 and rods 60. To release the rectifier discs so that they can be withdrawn, the levers 58 are pushed upwardly by means of rods 60 and handles 61 into the position of lever 58 shown in dashed lines until the lugs 57 are disengaged from the depressions in levers 56 whereupon these levers move under the influence of leaf springs 54 into the position shown dotted.

10 An insulating strip 62 is held on the upper surface of shelf 10 and formed with semi-circular portions to locate the rectifier discs in position. When levers 58 are pulled downwards to press springs 48 on to the rectifier discs, the springs 15 48 press down with a rolling motion, which prevents any scratching of the sprayed metal counter electrodes thereon.

The terminal 50 for each spring 48 is connected to the mid-point of two resistance spools 24 and 25. The other end of resistance 24 is connected to a bus bar 63 and the other end of resistance 25 to a bus bar 64. A common switch is provided for each shelf to connect the positive pole of the direct current supply either to bus-bar 63 or to bus bar 64 according to the size of the rectifier discs undergoing electrical treatment. The negative pole of the supply is connected to the framework and thus to the flat hollow plate 10.

What is claimed is:

1. Apparatus for the electrical treatment of selenium rectifiers comprising a channel for circulation of water, a flat surface for said channel on which the rectifiers are adapted to rest, means for circulating cooling water through said channel, means for holding said rectifiers in good heat conducting relation with the surface of said channel and contact means for connecting each of said rectifiers in series with an individual resistance in parallel to a common source of direct current.

2. Apparatus for electrical treatment of selenium rectifiers comprising a channel with means for circulating a cooling medium there-through, a flat surface of said channel for supporting rectifiers, means for holding the rectifiers in good heat conducting relation with said surface, circuit means for connecting each of said rectifiers in series with an individual resistance in parallel to a common direct current source, said holding means comprising pressure applying means individual to each rectifier for pressing said rectifier against the surface of said channel and means for positioning the individual rectifiers beneath the pressure applying means.

3. Apparatus as claimed in claim 2 comprising means for positioning rectifiers of either of two different sizes beneath said pressure applying means, and switch means for connecting a resistance of either of two different values in series with the several rectifiers.

4. Apparatus as claimed in claim 2 in which said pressure applying means comprises a flexible metal bellows for each rectifier and means for admitting fluid under pressure to each bellows.

5. Apparatus as claimed in claim 2 in which said pressure applying means comprises a flexible metal bellows for each rectifier with means for admitting fluid under pressure to all said bellows simultaneously.

6. Apparatus as claimed in claim 2 in which said pressure applying means comprises a conical helical spring for each rectifier and means is provided for allowing all the springs to exert pressure on the respective rectifiers and means is

provided for freeing all the rectifiers simultaneously from spring pressure.

7. Apparatus as claimed in claim 2 in which said pressure applying means comprises for each rectifier a spring metal strip bent into a closed figure, all said strips being mounted upon a common bar, means being provided for locking said common bar in position to press each strip against its corresponding rectifier. 5

8. Apparatus as claimed in claim 2 comprising 10 a refrigeration plant located in the circulation channel of said cooling medium.
